UNITED STATES PATENT OFFICE.

FRANK H. FRENCH, OF PRESTON, IOWA.

TANDEM DISK HARROW.

1,337,448.

Specification of Letters Patent. Patented Apr. 20, 1920.

Application filed August 18, 1918. Serial No. 818,147.

To all whom it may concern:

Be it known that I, FRANK H. FRENCH, a citizen of the United States of America, and resident of Preston, Jackson county, Iowa, have invented a new and useful Tandem Disk Harrow, of which the following is a specification.

The object of this invention is to provide an improved construction for a tandem or trailer disk harrow.

A further object of this invention is to provide improved means for connecting the disk units of a trailer device, to prevent separation of said units in use.

15 A further object of this invention is to provide improved means for connecting a trailer disk harrow to a forward harrow.

20 A further object of this invention is to provide improved means for leveling or adjusting the elevation of trailer disk units or gangs.

25 A further object of this invention is to provide an improved construction for a trailer device which shall produce a tendency on the part of said trailer device to follow the course of a leader device.

30 A further object of this invention is to provide an improved construction for a wheeled trailer device whereby said trailer device tends to advance in a straight line so long as a leader device to which it is attached advances in a straight line, and whereby said trailer device automatically and instantly conforms to and follows the 35 leader device in any deviation from a straight course.

40 A further object of this invention is to provide an improved construction for a tandem disk harrow which automatically overcomes the tendency of said harrow to creep down the slope when advancing on a side hill.

45 My invention consists in the construction, arrangement and combination of elements hereinafter set forth, pointed out in my claims and illustrated by the accompanying drawings, in which—

50 Figure 1 is a plan illustrating my improved trailer disk harrow in position for practical use in connection with a forward disk harrow, a portion only of the latter device being shown. Fig. 2 is a side elevation of the same. Fig. 3 is a cross-section, on an enlarged scale, on the line 3—3 of Fig. 1. Fig. 4 is a detail plan of a portion

of the devices which operate automatically to effect the course of the trailer device. Fig. 5 is a longitudinal section of the same devices. Fig. 6 is a perspective illustrating one end portion of the frame member employed to connect the units of the trailer disk harrow, on an enlarged scale. Fig. 7 is a section, on an enlarged scale, on the line 7—7 of Fig. 1.

Fig. 8 is a fragmentary plan, and Fig. 9 a corresponding side elevation, illustrating a modified form of my connecting devices to hitch a trailer disk harrow to a forward disk harrow of different type from that illustrated in Figs. 1 and 2.

70 In Figs. 1 and 2 I have illustrated my improved trailer disk harrow used in connection with a leader disk harrow of special construction, such as is illustrated and described in Letters Patent of the United States Number 1,286,986 granted to me December 10, 1918. This leader disk harrow is comprised, generally of a relatively long main frame, designated generally by the numeral 10, having a length corresponding substantially to the combined lengths of the disk units or gangs 11, 12. Evener bars 13, 14 are pivoted at their centers to and on opposite sides of the center of the main frame 10, and have their outer ends pivotally connected, by means of links 15, 16 respectively, to extreme outer end portions of the respective disk gangs. Set levers 17, 18 are fulcrumed intermediate of their ends on the frame 10 and are adapted for adjustment for adjusting the inclination of the disk gangs relative to the line of draft. The lower ends of the set levers 17, 18 are pivotally connected by links 19, 20 to inner ends of the evener bars 13, 14, respectively, and by links 21, 22 to inner end portions of the disk gangs 11, 12 respectively. Thus it will be seen that rearward movement of the upper ends of the set levers 17, 18 will result in forward movement of the links 21, 22, causing a forward movement of the inner ends of the disk gangs; and in forward movement of the links 19, 20, causing an oscillation of the evener bars 13, 14, rearward movement of the links 15, 16 and of the outer ends of the disk gangs. An opposite movement of the levers will of course result in an opposite movement of the parts described. In this manner the disk gangs

90 95 100 105 110 are moved from both ends, in the process of

adjusting their inclination, and neither end need be moved a great distance as in the common forms. This general explanation of the forward disk harrow is given to make 5 clear the manner of connecting my improved trailer harrow to it.

The trailer harrow has two disk gangs, designated generally by the numerals 23, 24, the disks of which preferably are of the 10 familiar cutaway type, and arranged in staggered relation, and oppositely dished, relative to the disks of the forward harrow. At the extreme outer end portions of the gangs 23, 24, preferably between the two 15 outermost disks of each gang, are boxings 25, 26, each of which has a horizontal bearing 27 (Fig. 6) to receive an axle of a disk gang, and a forward projection 28 formed with a vertical bearing 28^a. A cross frame 20 bar 29 is formed of two spaced parallel members suitably secured together, is arranged above the disk gangs 23, 24, and has its end portions turned downwardly adjacent the boxings 25, 26. In the downturned end 25 portions of the cross frame bar 29 are secured spindles 30, 31, vertically arranged and projecting at both ends from said frame bar. The lower projecting ends of the spindles 30, 31 are swiveled in the vertical 30 bearings of the forward projections of the boxings, 25, 26, and secured as by cotter pins 32. The cross frame bar 29 provides a means for connecting the disk gangs 23, 24, and preventing their separation in use. 35 An evener bar 33 is transversely arranged in front of and substantially parallel with the cross frame bar 29, and may be considerably shorter than said frame bar. The evener bar 33 has its end portions hooked 40 or recurved rearwardly at 33^a and lying in the same horizontal plane as the body portion thereof. Draft links 34, 35 are arranged substantially horizontally and have their rear ends pivoted on projecting upper 45 ends of the spindles 30, 31, and their forward ends converging somewhat and overlying end portions of the evener bar 33 and pivoted to bolts 36, 37 extending vertically therethrough. Other draft links 38, 39 are 50 pivoted at their rear ends to lower end portions of the spindles 30, 31, are inclined upwardly throughout major portions of their lengths, and have their forward end portions bent into horizontal planes spaced below the draft links 34, 35. The forward 55 end portions of the lower draft links 38, 39 engage the lower surface of end portions of the evener bar 33 and are pivoted on the bolts 36, 37. Forward portions of the draft 60 links 34-38 and 35-39 also are connected by bolts 40, spacing blocks 41 being interposed between said members. Hammer-strap braces 43 extend from the bolts 40 to the bolts 36 and 37, the last named bolts 65 projecting materially above the evener bar

33. The recurved or hooked portions of the evener bar 33 are embraced between the parallel portions of the draft links 34-38 and 35-39, to prevent tilting of said bar under strain. Draft links 44, 45 are provided to connect end portions of the evener bar 33 to the frame of the forward disk harrow, said draft links preferably converging substantially on the same angles assumed by the rearmost draft links, so that they are 70 substantially in line, on each side of the device. Each draft link 44, 45 preferably is composed of two flat bars arranged with their greater transverse dimension vertically, the forward portions of which are side by 75 side and bolted rigidly together, as by bolts 46. Substantially midway of their ends the bars composing the draft links 44, 45 diverge to form vertically arranged forks, the rear ends of which are formed with eyes 80 pivoted on the bolts 36 and 37. The upper members of the forks are pivoted on upper end portions of the bolts 36 and 37, above the braces 43, and the lower members are pivoted on lower ends of said bolts, below 85 the lower rear draft links 38 and 39. The general form of the forward draft links 44, 45 is arched, whereby they are carried over the forward disk gangs 11, 12, the forward 90 end portions inclining downwardly toward 95 the centers of the evener bars 13, 14. U-clips 47, 47 are swiveled on the pivots of the evener bars 13, 14, and forward ends of the draft links 44, 45 enter said clips and are pivoted therein on transversely arranged 100 bolts 48. Special braces 49, 50 may be provided, extending from the pivots of the evener bars 13, 14 to the pole bars 51 of the forward harrow, on inclined lines conforming substantially to the inclination of 105 the draft links 34-38, 44, 35-39 and 45. Thus means is provided for transferring the draft force from the pole of the forward harrow to outer end portions of the trailer harrow, and for bridging the draft devices 110 over the harrow devices. The arrangement of the forward and rear draft links, and their connection to the evener bar 33, provides a means for accomplishing this bridging without resulting in weakened connections or a tendency to apply draft to the trailer devices on lines inclined from the horizontal. It should be stated that hammerstrap braces 52 are connected to upper 115 portions of the bolts 36, 37 and extend inwardly and downwardly and are connected to the evener bar 33. 120

A short tongue member 53 is provided and passes at its rear end beneath the central portion of the cross frame bar 29, and passes 125 at its forward end beneath, and is pivoted by a bolt 54 to, the central portion of the evener bar 33. A plate 55 overlies and is slidable on the forward portion of the tongue 53 and is formed at its forward end 130

with an upturned flange 56 bearing against the rear side of the evener bar 33, said flange preferably being elongated and extending a material distance each side of the pivot bolt 54. Portions of the plate 55 project laterally beyond side margins of the tongue 53 and are secured by bolts 57 to bar washers 58 underlying said tongue, whereby slide bearings are formed connecting the plate to the tongue. An upstanding bracket 59 is secured to the tongue 53 at a point beyond the rearward range of movement of the plate 55. A bolt 60 passes through the central portion of the flange 56 and has its head 10 countersunk in the front surface thereof. The forward end portion of the bolt 60 is threaded, and a lock nut 61 is screwed thereon, against the rear surface of the flange 56, to make a rigid connection between said members. The rear portion of the bolt 60 is reduced in diameter and passes slidably through an aperture in the bracket 59. A coil spring 62 is mounted on the bolt 60, between the bracket 59 and flange 56 and 20 is under tension and tends to hold said bracket and flange separately as widely as possible. I prefer to provide means for adjusting the tension of the spring 62, by placing a washer 63 and adjusting nut 64 on the threaded portion of the bolt 60, the washer receiving actual contact of the forward end of the spring.

Underslung sectors 65, 66 are fixed to and project forwardly and downwardly from the evener bar 33 adjacent but spaced from the ends thereof. Set levers 67, 68 are fulcrumed intermediate of their ends on the sectors 65, 66 and are provided with detent devices 69 for engaging them and holding 30 the levers in any position in which they may be placed manually. Set lever links 70, 71 are pivoted at their forward ends to the lower ends of the set levers, which project below the sectors, and said links extend rearwardly and inwardly and are pivoted at their rear ends to boxings 72, 73 carried by the inner ends of the rear disk gangs 23, 24. The levers 67, 68 may be shifted to adjust the inclination or degree of angularity of 40 the disk gangs relative to the line of draft.

A bracket 74 is mounted on and secured by bolts 75 to the central portion of the cross frame bar 29 and a sector 76 is formed on and rises from said bracket. An adjusting lever 77 is fulcrumed at its end on the sector 76 and is provided with detent devices 78 for engaging said sector to hold said lever in any position in which it may be placed manually. A yoke 79 is arranged with its closed end beneath the rear portion of the tongue 53 and has its arms extending beneath and beyond the cross frame bar 29. The arms of the yoke 79 contact with the lower surface of the cross frame bar and are secured 50 thereto by U-bolts 80 and washer plates 81, the U-bolts engaging the arms of the yoke with their closed ends and passing upwardly between the spaced members of the frame bar and through the washer plates 81, which are mounted on said frame bar. Brackets 70 55 82 are carried by and rise from forward portions of the yoke 79, and a rock shaft 83 is journaled in said brackets, and is formed with forwardly extending crank arms located outside of the brackets. On the central portion of the rock shaft 83 is an upwardly and forwardly extending lever arm 84 to which is pivotally connected a link 85 extending across an intermediate portion of the adjusting lever 77, said link being provided with a tension coil spring 86. Presser bars 87, 88 are mounted on opposite sides of the arms of the yoke 79 and are formed with upturned rear ends pivoted by bolts 89 to rear ends of said yoke arms. On the forward ends of the presser bars 87, 88 are secured upstanding brackets 90, to the upper ends of which are pivoted the end cranks of the rock shaft 83. The presser bars 87, 88 60 overlie portions of the frames of the disk gangs 23 and 24, or extensions of said frames, and downward movement of said presser bars causes a depression of inner end portions of the disk gangs. Such downward movement is accomplished by 65 pressure on the lever 77 downwardly, which acts through the link 85, lever arm 84, rock shaft 83 and brackets 90 to lower said presser bars, and an opposite movement of said lever will permit a raising of said 70 presser bars, and a release of pressure on the disk gang frames. The link 85 is not connected directly to the lever 77 but passes across said lever and is held by any convenient means against lateral displacement 75 relative thereto, while the direct pressure of the lever is received by the spring 86, a set collar 91 preferably being provided on said link at one end of the spring to permit adjustment of the tension of the said spring. 80 Thus a yielding connection is established between the lever and the rock shaft, so that under emergencies the presser bars may move upwardly somewhat independently of any movement of the lever. A yoke shaped 85 extension 92, shown in Fig. 3, preferably is fixed to each of the presser bars 87, 88 at its ends and passes beneath the frame member of the disk harrow loosely. It is the function of these extensions to prevent the gangs 90 from dropping out of place relative to the pressure devices.

In practical use the normal tension of the spring 62, acting upon the relatively long flange 56 of the plate 55, in contact with 120 the rear face of the evener bar 33, tends to maintain said evener bar in a position wherein it is parallel to the frame bar 29 and to said flange 56 and at right angles 125 to the tongue 53; in which position of the 130

various parts the disk gangs 23, 24 are in their normal positions of adjustment as determined by the adjusting levers 67, 68 and links 70, 71. Whenever anything occurs to 5 disturb this normal position and arrangement of the parts, in which the tongue 53 is at right angles to and the flange 56 parallel and in contact with the evener bar 33, the spring 62 is put under greater tension by 10 sliding rearward movement of the plate 55 on the tongue, resulting from pressure of the flange 56 at one end or the other against the evener bar, depending upon which direction it is inclined away from the latter 15 member. The disturbance of the normal position of the parts may occur through lateral draft on the forward portion of the tongue 53, as in rounding a corner; or it may occur through lateral draft on either 20 or both of the disk gangs, and hence on the rear portion of the tongue, as in traveling on a side hill or laterally inclined surface. In either event the lateral draft is transferred to the evener bar 33 to cause it to 25 move out of its normal condition at right angles to the tongue against the pressure of the spring 62, with the effect of placing said spring under greater tension as before stated. This shifting of the evener bar in- 30 cludes a relative forward movement of the end on that side of the tongue to which draft is applied, and such forward movement results in a forward draft on the corresponding link 70 or 71, with a correspond- 35 ing rearward thrust on the other of said links. This movement of the links 70, 71 in turn acts on the inner ends of the disk gangs, accomplishing a relative forward movement of the inner end of that gang on the side toward which the draft is effective, 40 and a corresponding rearward movement of the inner end of the other of said gangs, displacing them from their normal or adjusted positions of angularity, in equal degrees but opposite directions. In other words, some of the inclination or angularity is taken from the gang on one side and added to that on the other, the increase 45 in angularity or degree of inclination being on that side toward which draft is applied on the forward end of the tongue and on the evener bar. The result of this shifting of angularity of the follower devices is a 50 position by which they more readily follow the leader device in rounding a corner; and as soon as the side strain is removed, or reduced to a point below the effective force 55 of the tension spring, said spring acts to return the parts to their normal positions, in which the follower devices tend to advance in a straight path of travel.

In case the side strain on the tongue is produced at its rear end through lateral pull of the trailer devices in advancing on a 60 side hill or slope, the result is such as to

turn the trailer or follower devices, in this instance the disk gangs, in such fashion that they tend to advance slightly in an uphill direction, through the alteration of their angularity in a manner similar to that de- 70 scribed, and this alteration is sufficient to overcome the downhill pull, the result being that the implement advances in a straight line in spite of the downhill pull.

In Figs. 8 and 9 I have illustrated the ap- 75 plication of these devices and principles for the use of my improved trailer disk harrow and its connections with a leader disk harrow of the ordinary type, portions only of the devices being shown. The leader har- 80 row includes disk gangs 11^a, 12^a, a cross frame bar 10^a and angle pole bars 51^a at- tached thereto. The tandem or trailer har- 85 row is constructed as previously described herein with the single exception that the forward draft links 44, 45 are omitted and are substituted by a single forward draft link 44^a extending forwardly from the central portion of the evener bar 33, arching over the disk gangs 11^a, 12^a and their frames, 90 and pivotally connected at its forward end to the central portion of the cross frame bar 10^a. The action of the evener devices is the same as previously described.

The evener principles and devices may 95 also be applied to other trailer devices, such as tongue trucks, cultivators, harrow carts and the like, to cause said trailer devices to follow in the path of the leader or tractor device, whether in a straight line or on a 100 curve.

I claim as my invention—

1. In a trailer disk harrow, a cross frame member, disk gangs pivoted at their outer end portions to end portions of said frame member, an evener bar arranged parallel with and in front of said frame member, a tongue connected with the center of the frame member and pivoted to the center of said evener bar, draft links pivotally connecting end portions of the frame member and evener bar, set levers pivoted on said evener bar, and links connected with said set levers and pivotally connected to inner end portions of the respective disk gangs. 110

2. In a trailer disk harrow, a cross frame member, disk gangs pivoted at their outer end portions to end portions of said frame member, an evener bar arranged parallel with and in front of said frame member, a tongue connected with said frame member and pivoted to the center of said evener bar, means connected with said evener bar for independently adjusting the angularity of 120 said disk gangs, tension devices between said tongue and evener bar tending to hold them at right angles to each other for straight-ahead advance of the device but adapted to yield under pressure to permit oscillation of said disk gangs, and presser devices carried 125

by the rear portion of said tongue and adapted to engage inner ends of said disk gangs.

3. In a trailer disk harrow, a cross frame member, disk gangs pivoted at their outer end portions to end portions of said frame member, an evener bar arranged parallel with and in front of said frame member, a tongue connected with said frame member and pivoted to the center of said evener bar, means connected with said evener bar for independently adjusting the angularity of said disk gangs, and yielding pressure devices between said tongue and the evener bar tending normally to hold them at right angles to each other for straight-ahead advance of the device but adapted to yield when lateral pressure is applied, so that a portion of the adjusted angularity is removed from one of said disk gangs and a corresponding amount applied to the other.

4. In a trailer disk harrow, a cross frame member, disk gangs pivoted at their outer ends to end portions of said frame member, an evener bar arranged parallel with and in front of said frame member, a tongue connected with said frame member and pivoted to the center of said evener bar, draft links pivotally connecting end portions of the frame bar and evener bar, means for independently adjusting the angularity of said disk gangs, and yielding pressure devices between said tongue and the evener bar adapted normally to hold them at right angles to each other for straight-ahead advance of the device but adapted to yield under lateral pressure, so that a portion of the adjusted angularity is removed from one of said disk gangs and a corresponding amount applied to the other.

5. In a trailer disk harrow, a cross frame member, disk gangs pivoted at their outer ends to end portions of said frame member, an evener bar arranged parallel with and in front of said frame member, a tongue connected with said frame member and pivoted to the center of said evener bar, draft links pivotally connecting end portions of the frame bar and evener bar, means for adjusting the angularity of said disk gangs, a plate slidably mounted on said tongue and formed with an elongated flange engaging said evener bar, a tension spring engaging said plate and the tongue and adapted to hold said flange in such engagement, and means for adjusting the tension of said spring.

6. In a trailer disk harrow, a cross frame member, disk gangs pivoted at their outer ends to end portions of said frame member, an evener bar arranged parallel with and in front of said frame member, a tongue connected with said frame member and pivoted to the center of said evener bar, tension devices between said tongue and the evener

bar, draft links pivotally connecting end portions of said frame member to end portions of said evener bar, each of said links being formed of two members vertically spaced, said evener bar being recurved at its ends to form hooks engaging between the members of said draft links.

7. In a trailer disk harrow, disk gangs, an evener bar transversely arranged in front of said disk gangs, a tongue crossing and pivoted to the center of said evener bar, pivotal connections between end portions of said evener bar and outer end portions of the respective disk gangs, pivotal connections between inner ends of the disk gangs and said evener bar, and yielding pressure devices arranged between said tongue and the evener bar tending normally to hold them at right angles for straight-ahead advance of the machine but adapted to yield under lateral pressure, so that said disk gangs are oppositely inclined away from their normal positions in equal degrees.

8. In a trailer disk harrow, disk gangs, an evener bar transversely arranged in front of said disk gangs, a tongue crossing and pivoted to the center of said evener bar, pivotal connections between end portions of said evener bar and outer end portions of the respective disk gangs, pivotal connections between inner ends of the disk gangs and said evener bar, means for adjusting the latter connections to adjust the angularity of said disk gangs, and yielding pressure devices arranged between said tongue and the evener bar tending normally to maintain straight-ahead advance of the machine but adapted to yield under lateral pressure, so that said disk gangs are oppositely inclined away from their adjusted positions in equal degrees.

9. In a trailer disk harrow, disk gangs arranged end to end, a cross frame member, said frame member being provided with vertical spindles at its ends to which outer end portions of the respective gangs are pivoted, a member transversely arranged in front of said frame member, and draft links pivotally connecting end portions of said frame member to end portions of said forward member, each of said draft links being formed of a pair of vertically spaced members embracing said forward member and diverging rearwardly and pivoted on upper and lower ends of said spindles.

10. In a trailer disk harrow, a frame, disk gangs arranged end to end and pivoted at their outer ends to end portions of said frame, an evener bar arranged transversely in front of said disk gangs, draft links pivotally connecting end portions of said frame to end portions of said evener bar, links connecting inner ends of the gangs to said bar, a tongue pivoted to the center of said evener bar, said tongue extending

- rearwardly to said frame, a yoke horizontally arranged and connected to said tongue and passing beneath said frame and clamped thereto, presser devices pivoted on said yoke and engaging inner ends of the respective disk gangs, and means carried by said frame for vertically adjusting said presser devices.
11. In a disk harrow, a frame, disk gangs arranged end to end beneath said frame, a yoke horizontally secured to the central portion of said frame, presser devices pivoted at one end to said yoke and adapted to engage inner ends of the respective disk gangs, a rock shaft journaled in said yoke, said rock shaft being formed with crank arms pivotally connected to the presser devices, a lever fulcrumed on said frame, and connections from said lever for rocking said shaft.
12. In a disk harrow, disk gangs arranged end to end, a frame to which said gangs are connected, a yoke horizontally arranged and secured to the central portion of said frame, presser devices pivoted at one end to said yoke and adapted to engage inner ends of the disk gangs, a rock shaft journaled in
- said yoke, said rock shaft being formed with crank arms pivotally connected to the presser devices, a lever fulcrumed on said frame, and connections between said lever and the rock shaft for oscillating the latter, said connections including yielding devices permitting movement of said rock shaft at times independently of said lever.
13. In a disk harrow, a frame, disk gangs arranged end to end, presser devices pivoted at one end on said frame and adapted to engage over inner end portions of said disk gangs, a rock shaft journaled in said frame, said rock shaft being formed with crank arms connected to opposite ends of said presser devices, means for rocking said shaft, and retaining devices on said presser devices passing beneath portions of the frames of said disk gangs and adapted to prevent displacement thereof, relative to the presser devices.

Signed at Des Moines, in the county of Polk and State of Iowa, this 11th day of August, 1919.

FRANK H. FRENCH.
